Primary Examiner — Samantha Q Lawrence*Assistant Examiner* — Holly M Rodriguez(74) *Attorney, Agent, or Firm* — Coloplast Corp.,
Coloplast A/S; Nick Baumann(57) **CLAIM**

The ornamental design for an ostomy accessory, as shown and described.

DESCRIPTION

FIG. 1 is an isometric view of a design for an ostomy accessory.

FIG. 2 is a top view of the design for the ostomy accessory.

FIG. 3 is a bottom view of the design for the ostomy accessory.

FIG. 4 is a front side view of the design for the ostomy accessory.

FIG. 5 is a back side view of the design for the ostomy accessory.

FIG. 6 is a right side view of the design for the ostomy accessory; and,

FIG. 7 is a left side view of the design for the ostomy accessory.

The portions the article shown in broken lines form no part of the claimed design.

1 Claim, 7 Drawing Sheets(56)
